(57) **CLAIM**

The ornamental design for a mandible guard, as shown and described.

DESCRIPTION

FIG. 1 is a bottom, front, right side perspective view of a mandible guard showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The short dash—long dash broken lines in the figures represent boundaries of the claimed design and form no part thereof. All other broken lines illustrate portions of the mandible guard that form no part of the claimed design.
